UNITED STATES PATENT OFFICE.

FRANK R. CHILDREN, OF COUNCIL BLUFFS, IOWA, ASSIGNOR TO E. CHILDREN'S SONS MANUFACTURING COMPANY, OF COUNCIL BLUFFS, IOWA, A CORPORATION OF IOWA.

PUMP.

1,185,059.

Specification of Letters Patent.

Patented May 30, 1916.

Application filed March 29, 1912. Serial No. 687,291.

To all whom it may concern:

Be it known that I, FRANK R. CHILDREN, a citizen of the United States, residing in Council Bluffs, in the county of Pottawattamie and State of Iowa, have invented a new and useful Improvement in Pumps, of which the following is a specification.

This invention relates to improvements in pumps.

10 Another object of the invention is to provide a pump, such, for instance, as is used in transferring oils from a barrel, and which is adapted to be attached directly to the original barrel.

15 Another object of the invention is to so arrange and construct the delivery spout of the pump as to prevent loss of oil or other material due to dripping.

Another object of the invention is to provide a structure comprised of few parts, simple and compact in arrangement, and one which may be cheaply manufactured.

20 My invention furthermore consists in the novel construction of parts and devices and 25 in the novel combinations of parts and devices herein shown and described and more particularly specified in the claim.

25 In the drawing forming a part of this specification, Figure 1 is a vertical, sectional view, showing my improved pump attached to a barrel, the latter being shown as broken in order to get the same on the sheet. Fig. 2 is a partial, detail, vertical section, taken on the line 2—2 of Fig. 1. Fig. 3 is a horizontal 35 sectional view, taken on the line 3—3 of Fig. 1, and Fig. 4 is a transverse, horizontal section, taken on the line 4—4 of Fig. 1.

30 In the drawing, I have shown the pump as comprising a cylinder or casing 10 within 40 which slides the piston 11, the latter comprising preferably a pair of leather washers 12 secured in place by washers 13 screwed on the lower end of a rack member 14. The rack member 14 is adapted to be reciprocated 45 up and down by means of a pinion 15 mounted on a shaft 16 supported in brackets 17 at the upper end of the casing or cylinder 10, the shaft 16 being provided with a crank arm 18, whereby the latter may be manually 50 operated. Screwed into the bottom of the piston or cylinder 10 and communicating with the interior of the latter is a T-pipe 19 having screwed thereinto on one side the elbow 20 and at the bottom thereof the inlet

55 pipe 21. Secured in the upper end of the inlet pipe 21 is a valve seat 22, preferably of soft metal and coöperating with a ball valve 23, the latter being limited in its upward movement by a pin 24 secured in the T-member 19. The inlet pipe 21 is provided 60 with a slidable sleeve 25 adapted to be adjustably retained in position on the pipe by means of a set screw 26. The sleeve 25 is exteriorly threaded and is adapted to fit an interiorly threaded bushing 26, such as is ordinarily provided on original barrels containing oil. I have shown the sleeve 25 as threaded into such a bushing in the top 27 of a barrel or inclosed receptacle 28 adapted for shipping oils or other liquids. Threaded 70 into the upturned end of the elbow 20 is a short nipple 29, the same being provided with a valve seat, preferably of soft metal 30 and in which is adapted to be seated a ball valve 31, the latter being limited in its upward movement by a pin 32 secured in the lower end of a vertically extending spout 33, the latter being attached to the nipple 29 by means of a coupling 34. The spout 33 is provided with a short, downturned end 35, 80 and at the joint or bend in the spout formed between the main portion of the spout and the downturned end 35 on the interior thereof is an upwardly extending ledge or projection 36.

85 With this structure it will be apparent that waste of oil or other liquid due to dripping will be prevented by this ledge 36, since the oil or liquid remaining in the tube, after the downward movement of the piston 11 has ceased, will fall back down the main portion of the spout 33. By making my improved pump in such a way that the same may be readily secured to original barrels containing oils or other liquids, I also 90 prevent the waste of oil or liquid due to transferring the oil from the original containers to a storage tank in the manner which has heretofore been customary. Another 95 advantage of my construction resides in the fact that the pump is readily interchangeable from one original barrel to another.

100 The pump is adjustable with respect to the barrel or other receptacle from which oil or other liquid is intended to be pumped, 105 by sliding of the pipe 21, as occasion may require, thus permitting it to be positioned accurately in close proximity to the bottom.

The pump is accurately adjustable to bring the spout over a desired delivery station through turning of the pump and the sleeve 25 in threaded connection with the bushing 5 46. These two features of adjustment together permit of rapid positioning of a pump in a new barrel, since the height of the pump may be gaged without respect to the position of the nozzle and the spout later 10 brought above the spot where it is desired to place receptacles to receive the contents of the barrel. Furthermore, such an arrangement permits the changing of the position of the spout in a horizontal plane without 15 out affecting the pipe adjustment.

By using the original receptacle for storage purposes, the contents are kept cleaner than by the old method where the oil or other liquid is transferred from the shipping 20 receptacle to a storage tank, and furthermore danger of loss from leaky faucets or valves and the consequent danger from fire where inflammable liquids are used is avoided by my method of using the original 25 container in connection with the pump. With my improved form of pump, it will be obvious, also that if there is any of the oil or other liquid spilled in the transferring of the liquid from the receptacle to the 30 measuring can, the same may be easily cleaned up and there will be no danger of

the drippings or spilled contents soaking into the floor.

I have shown one form of my invention, but it will be understood that the same is 35 merely illustrative and that many changes and variations may be made without departing from the spirit of the invention, and all such changes and variations are contemplated as fall within the scope of the ap- 40 pended claim.

I claim:

A pump having an upwardly extending outlet spout or pipe provided with a down-turned vertically extending nozzle at the 45 end thereof and being provided further with an upwardly extending sharp ledge projecting from the intersection of said pipe with said spout, said ledge forming a restricted passageway at the intersection of the main 50 portion of said pipe and the down-turned nozzle, the outer face of said ledge being disposed substantially in the plane of the adjacent face of said nozzle whereby to provide means for suddenly stopping the flow 55 of liquid through the spout without subsequent drip or waste.
